UNITED STATES PATENT OFFICE

HERMAN E. HARVEY, OF BELLEFONTAINE, OHIO

DESIGN FOR A PORTABLE BUILDING

Application filed August 7, 1931. Serial No. 40,797. Term of patent 14 years.

To all whom it may concern:

Be it known that I, HERMAN E. HARVEY, a citizen of the United States, residing at Bellefontaine, in the county of Logan and State of Ohio, have invented a new, original, and ornamental Design for a Portable Building, of which the following is a specification, reference being had to the accompanying drawing, forming part thereof.

The drawing shows a perspective view of the portable building.

The dominant feature of the design is the Saracenic arch construction of the combined

preformed sidewall and roof units which are connected together over the center line of the building with ornamental shingles applied over the sheathing at the roof portions and bends of the units. The opposite side of the building would be the same as that shown in the drawing, while the opposite end would be the same, or the door and windows omitted.

I claim:

The ornamental design for a portable building substantially as shown and described.

HERMAN E. HARVEY.
